UNITED STATES PATENT OFFICE.

JEAN F. WEBB, JR., OF NEW YORK, N. Y., ASSIGNOR TO THE INTERNATIONAL SIGNAL COMPANY, OF NEW YORK, N. Y., A CORPORATION.

PATH-CLEARING APPARATUS.

1,190,611.

Specification of Letters Patent. Patented July 11, 1916.

Application filed April 27, 1914. Serial No. 834,867.

To all whom it may concern:

Be it known that I, JEAN F. WEBB, Jr., residing at New York, in the county of New York and State of New York, have invented 5 certain new and useful Improvements in Path-Clearing Apparatus, of which the following is a specification.

My invention relates to certain new and useful improvements in train stopping apparatus.

In the art of train stopping apparatus there has become known a type which employs a train carried mechanism that includes a member (either in the form of an 15 arm, a plunger or a shoe, or a combination of these) which is adapted to contact with members located adjacent to the track along the right of way. It has been found in practice, particularly in northern locations, 20 that accumulations of snow, ice, frozen dirt, etc., frequently interfere with the proper operation of the apparatus, due to the fact that such accumulations of debris prevent the proper and timely contact between the 25 track and train carried members.

It is therefore the primary object of the present invention to provide a means whereby by the path of travel of the train carried member may be cleared of obstructions so 30 that when the train carried member comes into operative position with relation to the track member or members, the proper operation of the parts will be assured.

More subordinately the invention includes 35 a mechanism which may be attached to any train stopping apparatus that employs an arm or plunger to engage a track member, although the invention is particularly useful in connection with the train stopping 40 apparatus which forms the subject-matter of my co-pending application filed on even date herewith, Serial #834,865.

Again, the invention includes an attachment which is adapted to be secured to the 45 supporting casing of a train stopping apparatus, in advance of the actuating shoe of such apparatus, the attachment including a vertically disposed body that has a plow shoe at its lower end to aline with the 50 operating arm of plunger, and the shoe of the train stopping apparatus, and a support for such body, the support preferably having a cutting nose to laterally throw off obstructions encountered by it during the

travel of the apparatus along the right of way.

In its more subordinate nature the invention includes those novel details of construction, combination and arrangement of parts, all of which will be first fully described, and then be specifically pointed out in the appended claims, reference being had to the accompanying drawings, in which:

Figure 1 is a side elevation showing the invention as applied to a train stopping apparatus of the type disclosed in my co-pending application aforesaid. Fig. 2 is a section on the line 2—2 of Fig. 1, looking in the direction of the arrow. Fig. 3 is a horizontal section on the line 3—3 on Fig. 1. Fig. 4 is a detail horizontal section on the line 4—4 on Fig. 1.

Referring now to the accompanying drawings in which like letters and numerals of reference indicate like parts in all of the figures, 1 represents the housing of the train stopping apparatus which is provided with the necessary mechanism to effect the required action and which mechanism includes the vertically movable plunger 2, having a shoe 3 which is preferably beveled as at 4 to form a plow-like member (see Fig. 4). The bottom face 5, of the shoe 3, is preferably inclined slightly to the horizontal so that the sharpened edge of the shoe when 85 it engages the track member (not shown) will not be dulled.

6 designates the horizontal plane and by reference to Fig. 1, the inclination of the lower face of the shoe 3 will be apparent.

The support for the plunger 2 is preferably provided with a V-shaped nose 7 for a purpose later explained.

8 designates the housing which is provided with a flange 9 through which the 95 securing screws 10, that fasten the housing 8 to the train stopping mechanism's housing 1, pass. The housing 8 is preferably in the nature of a tubular body having its front face formed into a penetrating or cutting 100 nose 19 and the casing 8 is bored as at 11—12—13 to form a chamber in which the plunger 15, its stem 16, nut 17 and spring 18 are located.

Of course, when the member 2 of the train 105 stopping apparatus is a rigid contacting member only, the member 15 may be made correspondingly, but it is preferable to have

the members 2 and 15 in the nature of yieldable plungers.

The plunger 15 is provided with a shoe 20, the front face 31 of which is preferably 5 beveled from one side upwardly and transversely forwardly while the side face 22 is beveled upwardly and inwardly so as to plow loose the obstructions and throw them to one side. Instead of making the shoe 20 10 as thus described, it may be made as is the shoe 3 shown in Fig. 4.

In practice I prefer to make both the shoes 20 and 3 with sharpened edges so that they may both act as ice and snow plows, the 15 shoe 3 serving to plow loose any frozen material which the shoe 20 fails to loosen up. The under face 23 of the shoe 20 is preferably inclined from the horizontal to prevent dulling of the cutting edge.

20 The casing 8 is formed with a rearward extension 24 which is bifurcated at 25 and provided with set screws 26 for attachment to the nose 7 of the train stopping apparatus casing.

25 In practice, it will be observed that as the apparatus passes along the right of way, should any accumulation of snow, ice, frozen dirt, or other similar obstructions, be in the path of the apparatus, it will be plowed loose 30 and thrown to one side so as to insure the proper action of the plunger 2 of the train stopping apparatus.

From the foregoing description taken in connection with the accompanying drawings, it is thought the complete construction, 35 operation and advantages of my invention will be readily understood by those skilled in the art to which the invention relates.

What I claim is:

40 1. In an apparatus of the character stated, a rigid support, a plunger vertically movable in said support, a plow shoe carried by said plunger, said support including a penetrating nose.

45 2. In an apparatus of the character stated, a rigid support, a plunger vertically movable in said support, a plow shoe carried by said plunger, said support including a penetrating nose, a supplemental support secured 50 to the front of said rigid support, a rearwardly projecting arm carried by said supplemental support to engage said rigid support, a plunger yieldably mounted in said supplemental support and a plow shoe carried by said last named plunger.

55 3. In an apparatus of the character stated, a rigid support having a depending portion provided with a chamber, a plunger mount-

ed in said chamber, a shoe carried by said plunger, a supplemental support secured 60 near its upper end to said rigid support, said supplemental support having a rearwardly projecting arm secured to said depending portion of said rigid support, a plunger yieldably mounted in said supplemental support in advance of said first mentioned plunger, said second mentioned plunger having a plow shoe for clearing the path of movement.

4. In an apparatus of the character stated, 70 a rigid support having a depending portion provided with a chamber, a plunger mounted in said chamber, a shoe carried by said plunger, a supplemental support secured near its upper end to said rigid support, said supplemental support having a rearwardly projecting arm secured to said depending portion of said rigid support, a plunger yieldably mounted in said supplemental support in advance of said first mentioned plunger, said second mentioned plunger having a plow shoe for clearing the path of movement, 75 said supplemental support having a penetrating nose.

5. In an apparatus of the class described, 80 a support, a plunger yieldably mounted in said support, a cutting plow carried by said plunger for clearing the path of movement of the apparatus as a whole.

6. In an apparatus of the character stated, 90 a support, said support including a penetrating nose, said support having a bore, a plunger yieldably mounted in said bore, a shoe carried by said plunger, said shoe having a beveled portion to provide a cutting edge for clearing the path of movement 95 through which the apparatus is carried.

7. In an apparatus of the class described, a support and a yieldable contacting substantially flat bottom ramp cleaner, held to 100 the ramp with sufficient force to push aside the dirt, and to break up or melt away any ordinary sleet accumulations thereon.

8. In an apparatus of the class described, a support and a yieldable contacting substantially flat bottom ramp cleaner downwardly inclined from its front to its rear, and held to the ramp with sufficient force to 105 push aside the dirt and to break up or melt away any ordinary sleet accumulations 110 thereon.
